(57) **CLAIM**

The ornamental design for a reader housing as shown and described.

DESCRIPTION

FIG. 1 is an isometric view of a first embodiment of the reader housing;

FIG. 2 is a front view of the reader housing of FIG. 1;

FIG. 3 is a rear view of the reader housing of FIG. 1;

FIG. 4 is a left side view of the reader housing of FIG. 1;

FIG. 5 is a right side view of the reader housing of FIG. 1;

FIG. 6 is a top view of the reader housing of FIG. 1;

FIG. 7 is a bottom view of the reader housing of FIG. 1;

FIG. 8 is an isometric view of a second embodiment of the reader housing;

FIG. 9 is a front view of the reader housing of FIG. 8;

FIG. 10 is a rear view of the reader housing of FIG. 8;

FIG. 11 is a left side view of the reader housing of FIG. 8;

FIG. 12 is a right side view of the reader housing of FIG. 8;

FIG. 13 is a top view of the reader housing of FIG. 8; and,

FIG. 14 is a bottom view of the reader housing of FIG. 8.
